CONDUCTOR CENTERING ARRANGEMENT FOR TRAVELING FIELD TUBE

Gustav-Adolf Classe, Ulm (Danube), Germany, assignor to Telefunken Gesellschaft mit beschränkter Haftung, Hannover, Germany

Filed Sept. 26, 1960, Ser. No. 58,248

Claims priority, application Germany Sept. 29, 1959

10 Claims. (Cl. 315—3.5)

The present invention relates to an improvement in traveling field tubes, more particularly, to an arrangement for centering the spiral conductor within a plurality of insulating bars spaced around the periphery of the conductor.

It has been previously known to position a plurality of insulating bars around the spiral conductor of a traveling field tube in order to support the conductor. This arrangement resulted in rigidly mounting the spiral conductor to facilitate the conducting of the beam of electrons therethrough.

An alternative structure comprised the mounting of the spiral conductor between ceramic insulating bars with metal clamps mounted on the insulating bars and secured together by spot-welding. This arrangement was inherently disadvantageous as it rendered difficult the accurate adjustment of the several insulating bars. In addition, the use of spot-welds produced severe stresses and strains which, in turn, caused a displacement of the contact points between the insulating bars and the metal clamps.

The present invention is directed to improving the above-described arrangement so as to eliminate the disadvantages thereof. Accordingly, this invention provides an improved arrangement for mounting the spiral conductor within a plurality of insulating bars which surround the conductor.

The present invention essentially comprises a pair of tensioning rings which are rotatable with respect to each other and which surround the assembly of the spiral conductor and the insulating bars. The tensioning rings are in face-to-face relationship and have a plurality of substantially spiral-shaped cam surfaces on the edges of the central openings. These cam surfaces correspond in shape and position to the insulating bars. The cam surfaces are so shaped that rotation of the rings in one direction with respect to each other will urge the insulating bars against the spiral conductor so as to support the conductor in its central position.

It is therefore the principal object of this invention to provide a novel and improved arrangement for centering the spiral conductor within a plurality of insulating bars spaced about the periphery of the conductor in a traveling field tube.

It is another object of this invention to provide a simple and effective structure for centering the spiral conductor within a plurality of insulating bars spaced about the periphery of the conductor in a traveling field tube, whereby the components of the structure can be locked in position with respect to each other.

It is a further object of this invention to provide an arrangement for a traveling field tube for centering the spiral conductor between a plurality of insulating bars wherein the arrangement comprises a pair of flat members adjustable with respect to each other.

It is an additional object of this invention to provide an arrangement for a traveling field tube for centering the spiral conductor between a plurality of insulating bars, which arrangement can be selectively positioned along the length of the spiral conductor.

2

Other objects and advantages of this invention will become apparent upon reference to the accompanying description when taken in conjunction with the following drawings, wherein:

5 FIGURE 1 is an overall schematic view of a traveling field tube which embodies the present invention;

FIGURE 2 is a plan view of the tensioning ring arrangement and is essentially a transverse sectional view of the tube of FIGURE 1, but in enlarged scale, and

10 FIGURE 3 is an elevational view of the tensioning rings illustrated in FIGURE 2.

Proceeding next to the drawings, a specific embodiment of this invention will be described with particular reference to FIGURE 1 where there is generally illustrated a traveling field tube 1 in which is embodied the present invention. This tube comprises a casing 2 which is an essentially vacuum-sealed envelope. At one end of the envelope is a source of a stream of electrons or an electronic emitter 3 and at the other end of the tube

20 is a target 4.

A conventional spiral conductor 5 extends between the emitter and the target and is essentially positioned along the central longitudinal axis of the tube. There is a plurality of insulating bars 6 which are made of ceramic and which engage the outer periphery of the spiral conductor so as to support the conductor in this desired position. In this particular embodiment of the invention three insulating bars are employed. Positioned along the length of the spiral conductor are two pairs of

30 tensioning rings 7.

Proceeding next to FIGURE 2, the tensioning ring 7 is essentially a flat annular member having an outer periphery 8 and a central opening 9. The edge of the central opening 9 is formed to provide three equally spaced cam surfaces 10 which correspond in number and position to the insulating bars. The distance between the cam surfaces 10 and the center of the tensioning rings, as indicated at 11, gradually changes so that in effect the shape of the cam surfaces is that of a spiral.

40 The two tensioning rings comprising a pair are positioned in face-to-face relationship such as can be seen in FIGURE 3. The cam surfaces 10 of the rings of a pair are in reverse relationship, as is shown in FIGURE 2. As a result of this reverse relationship, rotation of the

45 nearer ring, as viewed in FIGURE 2, in a clockwise direction with respect to the further ring will urge the insulating bars 6 against the periphery of the conductor 5.

Conversely, rotation of the nearer ring of FIGURE 2 in the counter-clockwise direction will release the insulating bars from engagement with the spiral conductor. Since the cam surfaces are so selected to give clearance between the insulating bars and the cam surfaces when the tensioning rings have been rotated to release the insulating bars, a pair of tensioning rings can be slid over the

55 insulating bars to be positioned at any point along the length of the tube. By spacing the several pairs of rings from each other in a particular manner, the high-frequency characteristics of the tube can be varied. In addition, the tensioning rings may be used for suppressing many undesired forms of oscillation.

Another feature of this invention is the provision of means for locking together the pair of tensioning rings in a desired relationship. This may be done by spot-welds such as at 12 on the outer peripheries of the tensioning rings.

In addition, if the slopes of the cam surfaces 10 are made sufficiently gradual, the tensioning ring arrangement will be self-locking when the rings are rotated with re-

spect to each other when the insulating bars are urged against the conductor.

A structure is also provided on the rings for rotatively displacing the rings with respect to each other. One form of this structure is merely the making of holes or openings in the rings which holes then receive tools for rotating the rings.

As can be seen in FIGURE 3, bossed portions 13 are provided on the outer flat lateral faces of the tensioning rings. These bossed portions have depressions or recesses 14 for also receiving a tool for rotatively displacing the rings.

In addition, notches 15 may be provided in the outer periphery 8 of the tensioning rings for receiving tools for rotating the rings.

To ensure constant operating conditions within the tube the tensioning rings 7 are constructed of a material such as copper, so that the pressure is exerted by the insulating bars upon the spiral conductor elements substantially throughout the entire range of temperatures encountered within the tube. In addition, judicious selection of the tensioning ring material can be employed to influence the magnetic focusing field of the tube, so as to focus the beam of electrons, depending on whether a ferro-magnetic material such as iron or a non-magnetic material such as copper is used.

Thus it can be seen that the present invention has disclosed a simple and effective arrangement for centering the spiral conductor which is mounted between a plurality of insulating bars spaced about the periphery thereof. Further, this arrangement may be made self-locking so as to eliminate any necessity of spot-welding of the rings in a fixed relationship to each other. In addition, the locking arrangement facilitates a rapid adjustment of position of the tensioning rings with respect to the length of the tube.

It will be understood that this invention is susceptible to modification in order to adapt it to different usages and conditions and, accordingly, it is desired to comprehend such modifications within this invention as may fall within the scope of the appended claims.

Remarks.—Traveling field tube means traveling wave tube. Spiral conductor means helical wave guide.

What is claimed is:

1. In a traveling field tube, a spiral conductor, a plurality of insulating bars outwardly of said conductor and supporting the same, a pair of rings in face-to-face relationship surrounding said insulating bars, the inner edge of each ring having a plurality of cam surfaces corresponding in number and position to said insulating bars, the corresponding cam surfaces of said rings being in reverse relationship so that rotation of said rings in one direction with respect to each other will urge said bars against said conductor.

2. In a traveling field tube, a spiral conductor, a plurality of insulating bars outwardly of said conductor and supporting the same, a pair of flat annular members in face-to-face relationship and having openings therein with said conductor and bars passing therethrough, the inner edges of said openings having a plurality of spiral-shaped cam surfaces corresponding in number and position to said insulating bars, the corresponding cam surfaces of the annular members being in reverse relationship to each other so that rotation of said members with respect to each other in one position will urge said bars against said conductor.

3. In a traveling field tube, a spiral conductor, a plurality of insulating bars outwardly of said conductor and supporting the same, a pair of rings in face-to-face relationship surrounding said insulating bars, the inner edge of each ring having a plurality of spiral-shaped cam surfaces corresponding in number and position to said insulating bars, the corresponding cam surfaces of said rings being in reverse relationship so that rotation of said rings in one direction with respect to each other will

urge said bars against said conductor, and means for locking said rings with respect to each other.

4. In a traveling field tube, a spiral conductor, a plurality of insulating bars outwardly of said conductor and supporting the same, a pair of rings in face-to-face relationship surrounding said insulating bars, the inner edge of each ring having a plurality of spiral-shaped cam surfaces corresponding in number and position to said insulating bars, the corresponding cam surfaces of said rings being in reverse relationship so that rotation of said rings in one direction with respect to each other will urge said bars against said conductor, said rings being spot-welded in fixed relationship to each other.

5. In a traveling field tube, a spiral conductor, a plurality of insulating bars outwardly of said conductor and supporting the same, a pair of rings in face-to-face relationship surrounding said insulating bars, the inner edge of each ring having a plurality of spiral-shaped cam surfaces corresponding in number and position to said insulating bars, the corresponding cam surfaces of said rings being in reverse relationship so that rotation of said rings in one direction with respect to each other will urge said bars against said conductor, said rings having bosses with recesses therein for receiving a tool used for rotatively displacing said rings with respect to each other.

6. In a traveling field tube, a spiral conductor, a plurality of insulating bars outwardly of said conductor and supporting the same, a pair of rings in face-to-face relationship surrounding said insulating bars, the inner edge of each ring having a plurality of spiral-shaped cam surfaces corresponding in number and position to said insulating bars, the corresponding cam surfaces of said rings being in reverse relationship so that rotation of said rings in one direction with respect to each other will urge said bars against said conductor, said rings having notches on the peripheries thereof for receiving a tool used for rotatively displacing said rings with respect to each other.

7. In a traveling field tube, a spiral conductor, a plurality of insulating bars outwardly of said conductor and supporting the same, a pair of rings in face-to-face relationship surrounding said insulating bars, the inner edge of each ring having a plurality of spiral-shaped cam surfaces corresponding in number and position to said insulating bars, the corresponding cam surfaces of said rings being in reverse relationship so that rotation of said rings in one direction with respect to each other will urge said bars against said conductor, and means on said rings for receiving a tool used for rotatively displacing said rings with respect to each other.

8. An arrangement for centering a spiral conductor of a traveling field tube within insulating bars supporting the same and comprising a pair of flat annular members in face-to-face relationship and having openings therein with the conductor and insulating bars passing therethrough, the inner edges of said openings having a plurality of spiral-shaped cam surfaces corresponding in number and position to said insulating bars, the corresponding cam surfaces of the annular members being in reverse relationship to each other so that rotation of said members with respect to each other in one position will urge said bars against said conductor.

9. An arrangement for centering a spiral conductor of a traveling field tube within insulating bars supporting the same and comprising a pair of flat annular members in face-to-face relationship and having openings therein with the conductor and insulating bars passing therethrough, the inner edges of said openings having a plurality of spiral-shaped cam surfaces corresponding in number and position to said insulating bars, the corresponding cam surfaces of the annular members being in reverse relationship to each other so that rotation of said members with respect to each other in one position will urge said bars against said conductor, said flat annular members having bosses on the outer lateral surfaces thereof with each boss having a recess therein for receiving a tool

used for rotatively displacing said annular members with respect to each other.

10. In a traveling field tube, a spiral conductor positioned substantially along the central axis of the tube, a plurality of insulating bars extending longitudinally of said tube and engaging the periphery of said spiral conductor, a pair of flat circular annular members having central openings therein with said insulating bars and spiral conductor passing therethrough, the edges of said central openings having a plurality of equal spiral-shaped cam surfaces corresponding in number and position to said insulating bars, the corresponding cam surfaces of said circular members being in reverse relationship so that rotation of said annular members in one direction with respect to each other will urge said insulating bars against 15 the periphery of said conductor.
